UNITED STATES PATENT OFFICE.

THOMAS H. WOOD, OF PHILADELPHIA, PENNSYLVANIA.

COMBINED AUTOMATIC FLOOR AND SAFETY-CLUTCH FOR ELEVATORS.

SPECIFICATION forming part of Letters Patent No. 293,390, dated February 12, 1884.

Application filed July 16, 1883. (No model.)

To all whom it may concern:

Be it known that I, THOMAS H. WOOD, of Philadelphia, in the county of Philadelphia and State of Pennsylvania, have invented a new and Improved Combined Automatic Floor and Safety-Clutch for Elevators, of which the following is a full, clear, and exact description.

The object of my invention is to provide a new and improved safety-floor for elevator-shafts, which floor is opened and closed automatically by the car as the same rises and descends, and with which devices for opening and closing the floor a safety-clutch is combined, which holds the car in place whenever the cable by which the car is suspended breaks or gives way.

The invention consists in flexible floor-sections adapted to close the elevator-shaft, which sections are secured on drums provided at the ends with cog-wheels, which can be operated by racks projecting from the top and bottom of the car, whereby the floor-sections can be opened and closed as the car descends and rises.

The invention further consists in providing the bottom rack with an additional rack adapted to engage with vertical ratchet-bars held on the sides of the shaft, which two racks are attached to angle-levers pivoted on the sides of the elevator-car, at the lower part of the same, the upper ends of the angle-levers being secured to ropes united with a cable for raising the car, whereby, when the said cable breaks, the angle-levers will be released, and a spring acting on the same can press one of the racks against the ratchet-bar of the elevator-shaft, whereby the descending car will be arrested and held in place.

The invention also consists in various parts and details, and combinations of the same, as will be fully described and set forth herein-after.

Reference is to be had to the accompanying drawings, forming a part of this specification, in which similar letters of reference indicate corresponding parts in both the figures.

Figure 1 is a longitudinal side view of part of an elevator-shaft provided with my improved safety-floor and clutching device, parts being shown in section. Fig. 2 is an elevation

of the same, parts being broken out and others shown in section.

The sliding floor for closing the shaft at each floor of the building consists of two sections, A A, formed of a series of parallel strips, a, hinged together at the longitudinal edges in such a manner that the said sections A will be flexible, and can each be wound on a separate drum, B, journaled in the frame-work of the elevator-shaft, parallel with the strips forming the sections, which drums are each concealed by a curved casing, B'. Each drum is provided on one end with a cog-wheel, C, rigidly attached thereto, and between the end of the drum and cog-wheel a belt-pulley, D, is arranged, over which a cross rope or belt, E, passes, which passes over a belt-pulley, F, made integral with a cog-wheel, G, arranged above the floor H, the vertical plane of the cog-wheel G being parallel with the vertical plane of the cog-wheel C, and the said cog-wheel G being a short distance, in the direction toward the center of the drum B, from the cog-wheel C. The pulleys F and D are one above the other. If the cog-wheel C is turned, the drum B will be turned with it, and the floor-section A will be wound on the drum B, or unwound from the same, the side edges of the sections A being suitably guided in grooves in the horizontal beams J at the opening in the floor H. The cog-wheels C on the ends of the drums B are so arranged that they will be diagonally opposite each other. The elevator-car K, which is suspended by the cable L, is provided at 80 diagonally-opposite points with racks M, projecting above the top of the car, and so arranged in relation to the cog-wheels C that when the car rises or descends the said racks can engage with the said cog-wheels and can 85 rotate them. The racks N, projecting from the bottom of the car at the same sides at which racks M are fastened, are secured to angle-levers O, pivoted in recesses O' in the bottom corners of the sides of the car, and to the upper ends of the said levers O ropes P are attached, which pass through grooves P' in the sides of the car to the top of the same, the said ropes P passing over suitable guide-pulleys, b b'. The upper ends of the ropes P are attached to a cross-plate, Q, secured to the hook L', fastened to the lower end of the cable L,

which hook L' passes through a suitable eye or analogous device, R, on the roof of the car, the eye R and the hook L' being elongated to adapt the hook L' to move vertically in the eye. The racks N, projecting downward from the levers O, are so arranged in relation to the cog-wheels C and G that they will engage with the wheels G, but not with the wheels C, when the car rises and descends. Standards or vertical posts S are secured on the sides of the elevator-shaft, and to the said standards racks T are fastened, which are provided with upwardly-projecting teeth. With each rack N a rack, W, having downwardly-projecting teeth, is made integral, the said rack W being so arranged that it can engage with the upwardly-projecting teeth of the corresponding rack T. A spring, U, contained in a recess, U', acts on the upper end of the lever O and presses the same outward, whereby the rack W will be pressed in the direction toward the rack T. The pulleys F and D are provided with a rubber covering to prevent slipping of the belt or rope E; or, in place of the pulleys, 25 sprocket-wheels can be used, and a chain can be used in place of the belt or rope E. The elevator-car can be of any desired construction. The strips a have their longitudinal edges beveled on the under surfaces to facilitate the rolling of the sections, and each section A is provided at the outer edge with a check-lug, d, which strikes against the edges of the floor at h and prevents the flexible floor-sections A from being wound too far on the drums B. The sections A are provided at the middle of the inner edges with a recess, through which the cable L can pass.

The operation is as follows: As shown in Fig. 1, the floor-sections A close the shaft, 40 and if the elevator-car K rises the racks M will engage with the cog-wheels C, and will rotate the same and the drums B in the direction of the arrow a', whereby the flexible sections A will be wound on the drums B, thus permitting the car to pass. After the car has passed, the racks N engage with the cog-wheels G, and also rotate them in the direction of the arrow a', whereby the cog-wheels G and their drums B will be revolved in the inverse direction of the arrow a' as the belts E are crossed. If the drums B are rotated in the direction of the arrow a', the floor-sections A will be moved across the opening of the shaft, which is thus closed. If the elevator descends, the bottom 55 racks, N, revolve the cog-wheels G in the inverse direction of the arrow a', whereby the cog-wheels C will be revolved in the direction of the arrow a', and the sections A will be wound on the drums B, thus opening the elevator-shaft. After the car has passed downward, the racks M revolve the cog-wheels C in the inverse direction of the arrow a', whereby the flexible sections are moved across the shaft-opening, which is thus closed. By means of 60 the above-described device the elevator-car can open and close the sliding floors of the

shaft as it rises and descends. The floor-sections A may be very easily moved, there is no undue strain on the cable L, the car K is not jarred or jolted, and the elevator-shaft is closed at each floor. Accidents by persons falling down the elevator-shaft are thus prevented to a great extent, and in case of fire the elevator-shaft is not apt to act as a flue to conduct the fire to the upper stories of the building. The ropes P are so arranged that when the cross-piece of the eye R rests on the bottom of the hook L' the ropes P will be drawn upward sufficiently to compress the spring U, and thus throw the lower ends of the racks N W outward from the racks T, so that the racks W cannot engage with the racks T, and thus not interfere with the rising and descending of the elevator-car. If the cable L breaks or becomes released from the winding-drum, or any other part which holds the cable L taut gives way, the springs U will not be held compressed by the ropes P any longer, and will throw the upper ends of the levers O outward, thereby throwing the racks W against the racks T, so that the teeth of the two racks can engage, and will thus hold the elevator-car in place. The car is thus prevented from dropping to the bottom of the shaft in case the cable breaks or any like accident happens. The safety device does not interfere in any way with the free and easy movement of the car when rising or descending.

In place of the sections A, made of strips hinged together, flexible floors made in any other suitable manner may be used.

Having thus described my invention, I claim as new and desire to secure by Letters Patent—

1. Flexible floor-sections for closing elevator-shafts, combined with drums on which they are adapted to be wound, racks on the elevator-car, and cog-wheels connected with the drums, substantially as herein shown and described, and for the purpose set forth.

2. The combination, with flexible floor-sections for closing elevator-shafts, of drums on which the sections are wound, cog-wheels on the said drums, cog-wheels journaled in the frame of the elevator-shaft above the drums, pulleys connected with the upper cog-wheels, pulleys on the shafts, ropes or belts passing over the said pulleys, and racks secured on the car, substantially as herein shown and described, and for the purpose set forth.

3. The combination, with the flexible floor-sections A, secured on the drums B, of the cog-wheels C on the ends of the drums, the cog-wheels G, journaled in the elevator-frame above the shafts, and in a plane parallel with the plane of the cog-wheels C, the belts E, the belt-pulleys F, connected with the cog-wheels G, the pulleys D on the drum B, the racks M, projecting from the top of the car and adapted to engage with the cog-wheels C, and the racks N, projecting from the bottom of the car, and

adapted to engage with the cog-wheels G, substantially as herein shown and described, and for the purpose set forth.

4. The combination, with an elevator-car, 5 flexible floor-sections adapted to be wound on drums, and racks arranged in the shaft, of angle-levers pivoted to the lower sides of the car, and provided with racks on opposite sides, ropes attached to said levers and connected with the cable for raising the car, and a pinion arranged above the floor and connected with the floor-drums, substantially as herein shown and described.

5. The combination, with an elevator-car, 15 flexible floor-sections adapted to be wound on drums, and racks arranged in the shaft, of the angle-levers O, provided with the racks N W, the ropes P, secured to the upper ends of the levers and connected to the car-operating cable, the pinion G, and the belt E, connecting the pinion with the floor-drums, substantially as herein shown and described.

6. The combination, with the car K, of the racks W, secured to levers O, pivoted to 25 the side of the car, the springs U, the ropes P, the cable L, the elongated hook L', and the elongated eye R, substantially as herein shown and described, and for the purpose set forth.

7. Flexible floor-sections for closing an elevator-shaft, combined with drums to which the 30 said floor-sections are attached, and racks pro-

jecting from the top and bottom of the car for revolving the said drums, which bottom racks are attached to pivoted angle-levers, and are made integral with racks adapted to engage 35 with vertical ratchet-bars secured on the side of the elevator-shaft, substantially as herein shown and described, and for the purpose set forth.

8. The combination, with the flexible sections A, of the drums B, the cog-wheels C G, the belt-pulleys D F, the belts E and car K, the upwardly-projecting racks M, the downwardly-projecting racks N, made integral or connected with racks W, and attached to the 40 pivoted angle-levers O, the springs U, the ropes P, attached to the levers O and to the elevator-cable, and the vertical ratchet-bars T, substantially as herein shown and described, and for the purpose set forth. 50

9. The combination, with the drums B and means for rotating the drums by the movement of elevator, of the flexible floor-sections A, provided at their outer edges with the check-lugs d, for limiting the winding of 55 said sections on the drums, substantially as herein shown and described.
